US00D845765S

(12) **United States Design Patent** (10) Patent No.: **US D845,765 S**
Stammen et al. (45) Date of Patent: ** *Apr. 16, 2019

(54) **PUSH BUTTON CLOSURE**

(71) Applicant: **Stolle Machinery Company, LLC**,
Centennial, CO (US)

(72) Inventors: **Dennis C. Stammen**, Brookville, OH
(US); **Patrick K. McCarty**, Dayton,
OH (US)

(73) Assignee: **STOLLE MACHINERY COMPANY,
LLC**, Centennial, CO (US)

(*) Notice: This patent is subject to a terminal disclaimer.

(**) Term: **15 Years**

(21) Appl. No.: **29/637,831**

(22) Filed: **Feb. 22, 2018**

(51) LOC (11) Cl. **09-07**

(57) **CLAIM**

The ornamental design for a push button closure, as shown and described.

DESCRIPTION

FIG. 1 is a top perspective view of the push button closure; FIG. 2 is another top perspective view of the push button closure;

FIG. 3 is a bottom perspective view of the push button closure;

FIG. 4 is another bottom perspective of the push button closure;

FIG. 5 is a top plan view of the push button closure;

FIG. 6 is a bottom plan view of the push button closure;

FIG. 7 is a side elevational view of the push button closure; and,

(Continued)

FIG. 8 is a section view of the push button closure, taken in the direction of line 8-8 shown in FIG. 5.

1 Claim, 7 Drawing Sheets
